UNITED STATES PATENT OFFICE.

LEON S. DUNN AND ELISÉE GUELFF, OF POINT MARION, PENNSYLVANIA.

WRENCH.

1,066,003.

Specification of Letters Patent.

Patented July 1, 1913.

Application filed March 29, 1912. Serial No. 687,256.

To all whom it may concern:

Be it known that we, LEON S. DUNN and ELISÉE GUELFF, citizens of the United States of America, residing at Point Marion, 5 in the county of Fayette and State of Pennsylvania, have invented certain new and useful Improvements in Wrenches, of which the following is a specification, reference being had therein to the accompanying drawing.

This invention relates to wrenches, and the objects of our invention are, first, to provide a strong and durable quick-acting wrench; second, to furnish the adjustable 15 jaw of the wrench with a double locking mechanism; third, to provide a simple and inexpensive wrench that will facilitate the work of an artisan, and fourth, to provide a wrench consisting of comparatively few 20 parts that are easily and quickly assembled.

We attain the above objects by a mechanical construction that will be hereinafter specifically described and then claimed, and reference will now be had to the drawing, 25 wherein:

Figure 1 is a side elevation of a wrench in accordance with this invention, Fig. 2 is a front elevation of the same, Fig. 3 is a horizontal sectional view taken on the 30 line III—III of Fig. 1, and Fig. 4 is a perspective view of a detached locking yoke.

A wrench in accordance with our invention comprises a shank 1 that is rectangular in cross section, said shank having the front 35 side thereof provided with transverse teeth 2 and the rear side thereof with transverse teeth 3, the teeth 3 being arranged the reverse of the teeth 2. The outer end of the shank 1 has a fixed jaw 4 presenting a flat 40 gripping surface 5 at the front side of the shank 1, and the inner end of the shank has a detachable handle 6.

Slidably mounted upon the shank 1 is an adjustable jaw body 7 which has the outer 45 end thereof provided with a jaw 8 presenting a flat gripping surface 9 at the front side of the shank 1, said jaw coöperating with the jaw 4 in gripping the facets of a nut. The adjustable jaw body 7 has a longitudinal opening 10 providing clearance for 50 the shank 1, and said jaw body has trans-

verse slots 11 in the front and rear sides thereof, said slots being in communication with the longitudinal opening 10.

The body 7 is provided with a pair of 55 spaced grooves which are indicated by the reference character 12. One groove is arranged upon both sides and front edge and the other groove is arranged upon both sides and rear edge of said body 7. Slidably 60 mounted in the said grooves are oppositely disposed shiftable locking yokes 13. Each yoke has a cross head 14 and an inwardly projecting tooth 15 that extends into the slot 11 and engages the teeth of the shank 65 1. The yokes are reversely arranged and engaging the inner sides of the heads 14 of said yokes are flat compression springs 16 that are secured to the front and rear sides of the jaw body 7, as at 17. These springs retain 70 the locking yokes 13 in a normally locked position, and in order to slide the jaw body 7 upon the shank 1 it is necessary that one or the other of the yokes be shifted by pressing against the cross heads 14 of 75 the yoke.

By pressing upon the outermost yoke, the jaw body 7 can be adjusted toward the jaw 4 as the innermost yoke recedes over the teeth 3. By pressing the innermost yoke 80 the jaw body can be shifted toward the handle 6 with the outermost jaw receding over the teeth 2.

It is thought that the operation and utility of the wrench will be apparent without 85 further description, and while in the drawing there is illustrated a preferred embodiment of the invention, it is to be understood that the structural elements thereof are susceptible to such variations as fall within 90 the scope of the appended claim.

What we claim is:—

A wrench comprising a shank having its front and rear edges formed with teeth, an adjustable jaw body slidably mounted upon 95 the shank and having a pair of slots, one arranged near the outer end of the front edge of said body and the other near the inner end of the rear edge of said body, said body provided with spaced grooves, 100 one of said grooves arranged upon each side and front edge and the other upon both sides

and rear edge of said body, oppositely disposed shiftable yokes normally seated in said grooves, said grooves intersecting said slots, teeth carried by said yokes and extending through said slots and engaging with the teeth of the shank, cross heads connected to said yokes, and oppositely disposed flat springs secured to the edges of said body and having their free ends engaging said

5

10 cross heads for normally maintaining the

teeth carried by the yokes in engagement with the teeth of the shank.

In testimony whereof we affix our signatures in the presence of two witnesses.

LEON S. DUNN.
ELISÉE GUELFF.
